(57) CLAIM

The ornamental design for an audio apparatus, as shown and described.

DESCRIPTION

FIG. 1 is a front elevational view of a first embodiment of an audio apparatus;

FIG. 2 is a right-side elevational view of the first embodiment thereof;

FIG. 3 is a rear elevational view of the first embodiment thereof;

FIG. 4 is a left-side elevational of the first embodiment view thereof;

FIG. 5 is a top plan view of the first embodiment thereof;

FIG. 6 is a bottom plan view of the first embodiment thereof;

FIG. 7 is a top perspective view of the first embodiment thereof

FIG. 8 is a front elevational view of a second embodiment of the audio apparatus;

FIG. 9 is a right-side elevational view of the second embodiment thereof;

FIG. 10 is a rear elevational view of the second embodiment thereof;

FIG. 11 is a left-side elevational of the second embodiment view thereof;

FIG. 12 is a top plan view of the second embodiment thereof;

FIG. 13 is a bottom plan view of the second embodiment thereof; and,

FIG. 14 is a top perspective view of the second embodiment thereof.

The broken lines shown in the drawings are for the purposes of illustrating portions of the article that form no part of the claimed design.
